UNITED STATES PATENT OFFICE.

JOHN C. McDONALD, OF NEW YORK, N. Y.

RAILWAY-TRAIN-CONTROLLING SYSTEM.

1,151,026.

Specification of Letters Patent. Patented Aug. 24, 1915.

Application filed December 10, 1912, Serial No. 736,011. Renewed January 21, 1915. Serial No. 3,630.

To all whom it may concern:

Be it known that I, JOHN C. McDONALD, a citizen of the United States, and a resident of New York, in the county of New York and State of New York, have invented certain new and useful Improvements in Railway-Train-Controlling Systems, of which the following is a specification.

My invention relates to improvements in railway train-controlling systems, particularly electric railway block systems and combined block and signal systems; though as hereinafter described, the invention is not limited in its application to electric railway systems.

As applied to an electric railway system, my invention comprises means whereby power is cut off from a motor car or train seeking to enter a block already occupied, also means whereby sections of a power conductor which are not at the moment required to be energized are grounded until required to be energized, also means for guarding trains which may, by accident or otherwise, drift beyond sections of the block in which they should come to rest.

Other features of my invention will be pointed out hereafter.

The objects of my invention are to facilitate the operation of railways, particularly electric railways, to reduce the danger of collisions, to provide simple means for grounding power conductors which are not at the moment required to be energized, to provide simple means for protecting trains which may drift beyond sections in which they should come to rest, and generally to make the circuits and apparatus of the system simple and reliable and to cause such circuits and apparatus to afford ample protection to trains.

The invention herein described comprises the system, circuits and apparatus of my application filed October 9, 1911, Sr. No. 653,477, with certain additions and modifications, as hereinafter pointed out.

I will now proceed to describe my invention with reference to the accompanying drawings, and will then point out the novel features in claims.

In said drawings: Figure 1 is a diagrammatic view showing the circuits and switches of one track of a double track electric railway system embodying my invention, the direction of normal progress along such track being indicated by an arrow. Fig. 2 is a

side view and Fig. 3 an end view of one of the switches employed in my system. Figs. 4, 5 and 6 are detail views of the contact mechanism of such switch, Figs. 4 and 6 being central longitudinal sections looking in opposite directions respectively, and Fig. 5 being a transverse section. Fig. 7 shows on a smaller scale, a longitudinal section of a two compartment switch, such as indicated in Fig. 1, and Fig. 8 is a transverse section of the two compartments of such switch, indicating the arrangement of contact points therein. Fig. 9 is a diagrammatic view illustrating the application of my invention to the control of trains propelled by means other than electric power drive from a power conductor located along the track.

According to my invention, as preferably applied to electric railways, current is communicated to the motors of a car or train on the track through a sectional conductor having as many sections as there are blocks; which conductor may conveniently be a third rail, though it might also be a trolley wire. To each section of such conductor current is communicated from a feed wire through a suitable switch controlled by track circuits; to which end one of the track rails is divided into as many insulated sections as there are blocks, the other rail (which is a ground or return rail) not being so divided.

The switches which I prefer to employ are mercurial switches operated by electromagnets, each such magnet being controlled by one of the track circuits.

Referring first to Fig. 1, T designates the track rail which is not divided into block sections, and T¹, T², etc., designate block sections of the other track rail. R¹, R², etc., designate corresponding sections of the current supply conductor. Current is supplied to the various power rail sections R¹, R², R³, etc., through a feed conductor F, and through switches S¹, S², etc., and conductor 17, there being one such switch for each block. Without limiting myself to any particular variety of switch I will state that I prefer a mercurial contact switch of the construction illustrated in Figs. 2-6 inclusive, and comprising an oscillatory barrel 1, constructed to contain mercury or other suitable fluid conductor, and pivoted on an axis 2 somewhat above the geometric center of the drum 1. The switch further comprises an arm 3 connected to such barrel 1, an electro-

magnet 4, an armature 5, for moving the barrel in one direction (the magnet and armature illustrated being of solenoid and plunger type) and a retractile spring 6. The barrel 1 is customarily provided internally with a layer of mercury 7, of suitable depth, and to keep the surface of this mercury clean, and also to reduce evaporation, and prevent sparking, the surface of the mercury may be covered with a layer 8, of oil or the like, of suitable depth; such oil being a good insulator. The barrel 1 is further provided with two sets of contact points, one set being numbered 9 and 10, the other set being numbered 11 and 12. It will be understood that the drum 1 is constructed of some non-conducting material, so that the contact pieces 9-12 inclusive are insulated from each other, except as they dip into the mercury, or that other suitable means are employed to insulate the contact pieces one from another. The location of the various contact pieces is such that contacts 9 and 10 are immersed in the mercury when the switch barrel 1 is in its normal position; the contacts 11 and 12 being then out of mercury; and that when the switch barrel is in its abnormal position, produced by energization of the magnet 4, contacts 11 and 12 will be immersed in the mercury, and contacts 9 and 10 will be out of the mercury and therefore insulated from one another.

Referring now again to Fig. 1, and considering the circuits of the system. The circuit of the switch magnet 4 of each block is controlled by the track circuit of that block, and also by the contact points of a switch of one of the blocks beyond. Customarily it is considered sufficient to maintain a train interval of not more than two blocks, between trains, and therefore in Fig. 1 I have shown the circuit of each switch magnet 4 controlled by the contact points 9 and 10 of a switch two blocks ahead; but it will be obvious that the circuit of each switch magnet 4 might be controlled by the contacts of corresponding switches either a less number of blocks or a greater number of blocks ahead.

Considering now the switch-operating circuit of one of the blocks, block T^1 for example, 13 designates a circuit conductor connected to rail section T^1 and passing through magnet 4 of switch S^1 and thence passing through contacts of a switch U^3 hereinafter mentioned to contact 10 of switch S^3 . From contact 9 of that switch S^3 , the circuit passes through a conductor 14 to a common return conductor 15 and thence to one pole of a switch-operating generator 16, diagrammatically represented in the drawing as a battery, the other pole of which is grounded. Rail T being grounded, it will be apparent that when a car or train enters block T^1 , the

wheels of such car or train will complete the track circuit from T to T^1 , thereby completing a circuit from the grounded side of generator 16, through rail T , the wheels and axles of the train, the rail T^1 , the magnet 4 of switch S^1 , to contact 10 of switch S^3 (neglecting for the moment switch U^3). If switch S^3 is in its normal position (as it will be if block T^3 is not occupied), this circuit will further be completed from contact point 10 through the mercury of switch S^3 to contact 9 of switch S^3 , to conductor 14 and thence through conductor 15 back to battery 16. The completion of this circuit will energize magnet 4 of switch S^1 , causing said magnet to swing the switch barrel 1 of switch S^1 to one side, and thereby operating certain signal circuits as well as protecting the train from other trains in rear, as will be described presently, and also connecting rail R^1 , to feed wire F . Supposing, however, that the block T^3 is occupied when a train enters block T^1 . In such case, since the track circuit of block T^3 passing through magnet 4 of switch S^3 of that block T^3 , is completed through the wheels and axles of the car or train of the block T^3 , the switch S^3 will be in its abnormal or operating position when the second train seeks to enter block T^1 , and therefore the barrel of switch S^3 will be in its abnormal position, contacts 9 and 10 of switch S^3 will be insulated from one another, and contacts 11 and 12 of switch S^3 will be connected through the mercury of switch S^3 . The function of these contacts 11 and 12 will be described presently. Since, with block T^3 occupied, the train entering block T^1 cannot complete the circuit through the magnet 4 of switch S^1 , because such circuit is broken at contact 9 and 10 of switch S^3 , it follows that the train entering block T^1 can receive no current from power conductor section R^1 , and therefore the train entering block T^1 must (except in exceptional instances as described hereinafter) come to rest shortly after entering that block, and must remain at rest until block T^3 is no longer occupied. As soon as the car or train on the block T^3 passes out of that block, the barrel of switch S^3 will return to normal position by gravity, and thereupon the track circuit of magnet 4 of switch S^1 of block T^1 , will be completed through contacts 9 and 10 of switch S^3 , and the train in block T^1 may proceed.

The sections R^1 , R^2 , etc., of the power rail overlap somewhat the corresponding sections T^1 , T^2 , of the sectional track rail.

With the sectional power conductor system above described, I preferably combine a signal system, the circuits of which are controlled by the same switches which control the power circuits. The contacts 11 and 12 of each switch are signal-circuit contacts. Considering the signal circuits of the block

T^3 , it will be seen that when contacts 11 and 12 of switch S^3 are connected through the mercury of that switch, not only is the power circuit complete from feed wire F to contacts 12 and 11, of switch S^3 , and wire 17 to power conductor section R^3 , but also a signal circuit is complete from feed wire F through contacts 12 and 11, and signal wire 18 to a danger signal D of the preceding block and to a caution signal C of block T^1 . These danger and caution signals may be of any suitable construction; but I have indicated electric lamps for the purpose. As is customary in ordinary railway work, where lamps or the like are used for signals, the danger signal lamps will be of one color and the caution signal lamps will be of another color. In the drawings I have indicated the danger signal lamps by the symbol $\bigcirc$ and the caution signal lamps by the symbol $\odot$. It will be seen therefore that when a car or train seeks to enter a block, R^1 for example, when the second block ahead is occupied, the motorman will find the caution lamps of the block which he is seeking to enter, lighted, and will thereby be notified to bring his train to rest before entering the dead rail section R^1 . Should the train in block T^3 leave that block by backing into block T^2 , then as soon as such train enters block T^2 and before it has left block T^3 , it will actuate switch S^2 and thereby will illuminate the danger signal lamps D of block T^1 ; so that notwithstanding when such train of the block T^3 has passed entirely from block T^3 to T^2 and so has permitted operation of switch S^1 , the train seeking to enter block T^1 will be debarred from preceding on in that block, by the danger signal D. So far as described, the system and circuits (except as to the switches U^1 , U^2 , U^3 , etc., which up to this point have been neglected) are the same as that of my said prior application Sr. No. 653,477. For each block there is, in addition to the main switch S^1 , or S^2 , or S^3 , etc., an additional switch, U^1 , or U^2 , or U^3 , etc., of similar construction to the switch S^1 , or S^2 , or S^3 , etc., except that these switches U^1 , U^2 , U^3 , etc., are double switches, and except that they are provided with contact points on one side of the barrel only. These switches U^1 , U^2 , U^3 , etc., are operated by magnets 19 bridged across from conductor 17 to return conductor 14; so that when a magnet 4 of one of the switches S is energized, the corresponding magnet 19 of the corresponding switch U must also be energized. Each of these switches U consists of a barrel divided by a transverse insulating partition 20 (Fig. 7) into two compartments, 21 and 22, each compartment 21 having two contact pieces 23 and 24, which are connected electrically by the mercury in that compartment 21 when the switch is in normal position, each compartment 22 hav-

ing two brushes 25 and 26, which are connected electrically by the mercury in that compartment 22 when the switch is in normal position. The contact pieces 23 and 24 are included in the circuit conductor leading from the insulating track section (T^1 , or T^2 , or T^3 , etc.,) of the second block in rear through the switch magnet 4 of that second block in rear, to the contact piece 10 of the block at which is located the particular switch U under consideration. The contact piece 26 of each switch U is connected to the circuit 17-18 of the block at which that particular switch U is located, and the corresponding contact piece 25 is connected to ground, these contact pieces 25 and 26 therefore serving to connect to ground the insulated power conductor section R^1 , or R^2 , or R^3 , etc., of that particular block. These switches U have two functions, the first of which is as follows: Suppose that a train is stalled on section T^5 for example. The switch S^5 is then in abnormal position, preventing a train which may enter block T^3 from receiving current in case it reaches power conductor R^3 . This train entering block T^3 should come to rest before it leaves block T^2 altogether; but suppose this train entering block T^3 nevertheless drifts so far into block T^3 as to leave block T^2 altogether. The train on block T^3 is then without signal protection behind it (except as to the action of switch U^3 now to be described); for since switch T^3 is compelled to remain in normal position through a train being on block T^5 , the signal D of block T^2 and the signal C of block T^1 are still at safety, and switch S^1 might be operated by a train now entering block T^1 (except for the action of switch U^3). While the train on block T^5 prevents switch S^3 from going to abnormal position when the second train enters block T^3 , it does not prevent the switch U^3 from going to abnormal position, so that promptly upon the entry of a train in the block T^3 , when block T^5 is occupied, the magnet 19 of switch U^3 is energized through completion of the circuit from rail T^3 through conductor 13 to magnet 19 of switch U^3 , and thence to conductor 14 and through conductor 15 and generator 16 back to ground, and contact pieces 23 and 24 of switch U^3 then break the circuit of magnet 4 of switch S^1 , so preventing the operation of switch S^1 , in case a train should enter the block. And the switch U^1 in like manner protects the rear of the train entering block T^1 . In like manner, if a train is stalled on any switch or block, and one of the signal wires is broken, the switch S of the block two blocks in rear might be operated by a train entering that block two blocks in rear, so, except for the action of the switch U of the block in which the train ahead is at the moment, allowing such rear train to proceed into the block

which it is entering. But the switch U of the block which the train ahead occupies prevents this. When these additional switches U are used, the sections or blocks 5 may be made of any desired length.

Another function of the extra switches U is to ground the corresponding power rails R¹, R², etc., when the corresponding blocks are not occupied by trains. When each 10 switch U is in normal position the corresponding power rail R is grounded as follows: from that power rail, through the corresponding conductor 17 and the corresponding conductor 18 to the contact piece 26 of the corresponding switch U and thence through the mercury of that switch to the corresponding contact piece 25 and thence to ground. This ground connection is broken by the operation of the switch U as soon as 20 the corresponding block is entered by a train; and when the train passes out of that block, the switch U, returning to normal, reestablishes the ground connection. Such ground connection renders idle sections of 25 the power rail inert and harmless, except when required to be energized by the presence of a train on the corresponding block, and also discharges each section of the power rail immediately the train passes from the 30 corresponding block.

In the following claims, the switches S¹, S², etc., are termed primary switches, and the switches U¹, U², etc., are termed secondary switches.

35 The train controlling system herein illustrated and described is applicable to the control of trains propelled by means other than electrical power, derived from a power conductor located along the track. This is 40 illustrated in Fig. 9, in which P designates a sectional controlling circuit rail, corresponding in all respects to the sectional power rail R of Fig. 1, except that this rail P is not employed for the supply of propulsion current, but is merely employed for the supply of current to operate a magnet Q on the locomotive or car; this magnet Q controlling an air brake valve 27 or a power-supply valve 28; or both, in such manner 45 that when the magnet is energized the air brake valve is closed and the power controlling valve is open. The locomotive or other car upon which this electrically-controlled valve mechanism is mounted, is provided 50 with a suitable contact shoe 29 making contact with the rail P; and a circuit conductor 30 leads from this shoe to the magnet Q and thence is grounded to the frame of the car or locomotive. The supply of current to 55 the sections of the rail P is controlled in precisely the same manner as is the supply of current to the sections of the rail R controlled, in Fig. 1. It follows therefore that 60 so long as any section of the rail P with 65 which the shoe 29 may be in contact at any

moment, is energized, the train may proceed; but when this section is deenergized, by the action of one of the switches S or U, the brakes will be applied, and the power cut off and the train brought to rest.

70

What I claim is:—

1. A railway train-controlling system comprising in combination a power conductor divided into sections, means for supplying current to the several sections of said conductor, comprising a primary electrically-controlled switch for each such section, a secondary electrically controlled switch for each such section, and track circuits including means for operating said switches, 75 the track circuit for each such primary switch passing through contacts of both the primary and secondary switches of a section in advance, which contacts are closed when such primary and secondary advance 80 switches are in clear position, and are broken when such primary and secondary advance switches are in danger position, the track circuit of the secondary switch of each such section being free from such control by 85 an advance switch; whereby each secondary switch is caused to occupy the danger position when a train is operating its track circuit independent of the operation or non-operation of the corresponding primary 90 switch.

2. A railway train-controlling system comprising in combination a power conductor divided into sections, means for supplying current to the several sections of said conductor, comprising a primary electrically-controlled switch for each such section, a secondary electrically controlled switch for each section, and track circuits including 100 means for operating said switches, the track circuit for each such primary switch passing through contacts of both the primary and secondary switches of a section in advance, which contacts are closed when such primary and secondary advance switches are 105 in clear position, and are broken when such primary and secondary advance switches are in danger position, the track circuit of the secondary switch of each such section being free from such control by an advance 110 switch; whereby each secondary switch is caused to occupy the danger position when a train is operating its track circuit, independent of the operation or non-operation of the corresponding primary switch, one of 115 said switches of each such section comprising means for grounding the corresponding 120 section when such switch is in clear position.

3. A railway train-controlling system 125 comprising in combination a power conductor divided into sections, means for supplying current to the several sections of said conductor, comprising a primary electrically-controlled switch for each such section, 130

a secondary electrically controlled switch for each such section, and circuits including means for operating such switches, arranged to be operated by trains, the circuit for each such primary switch passing through contacts of both the primary and the secondary 30 switch of a section in advance, which contacts are closed when such advance switches are in clear position, and are broken when such advance switches are in danger position, the controlling circuit of each such secondary switch being free from such control by an advance switch, whereby each secondary switch is caused to occupy the danger 35 position when a train is operating its controlling circuit independent of the operation or non-operation of the corresponding primary switch.

4. A railway train-controlling system 20 comprising in combination a power conductor divided into sections, means for supplying current to the several sections of said conductor, comprising a primary electrically-controlled switch for each such section, 25 a secondary electrically controlled switch for each such section, and circuits comprising means for operating such switches, arranged to be operated by trains, the circuit for each such primary switch passing through contacts of both the primary and the secondary 30 switch of a section in advance, which contacts are closed when such advance switches are in clear position, and are broken when such advance switches are in danger position, the controlling circuit of each such secondary switch being free from such control by an advance switch, whereby each secondary switch is caused to occupy the danger 35 position when a train is operating its controlling circuit independent of the operation or non-operation of the corresponding primary switch.

In testimony whereof I have signed this specification in the presence of two subscribing witnesses.

JOHN C. McDONALD.
